SWING-ARM FUEL DISPENSER FOR SERVICE STATIONS

John S. Loy, Elmer A. Robbins, and Melvin C. Hankel,
Fort Wayne, Ind., assignors to Tokheim Corporation,
Fort Wayne, Ind.

Filed May 21, 1973, Ser. No. 361,891

Term of patent 14 years

Int. Cl. D20—02

U.S. Cl. D52—2 A

FIG. 1

FIG. 2

FIG - 3

FIG - 4

FIG - 5

FIG. 1 is a left front perspective view of a swing-arm fuel dispenser for service stations showing our new design;
FIG. 2 is a rear elevational view thereof;
FIG. 3 is a front elevational view thereof;
FIG. 4 is a bottom elevational view thereof; and
FIG. 5 is a top elevational view thereof.

We claim:

The ornamental design for a swing-arm fuel dispenser for service stations, substantially as shown and described.
